UNITED STATES PATENT OFFICE.

HENRY MANN, OF MILWAUKEE, WISCONSIN.

DESIGN FOR A HOOP FOR BARRELS, &c.

SPECIFICATION forming part of Design No. 30,338, dated March 14, 1899.

Application filed February 17, 1899. Serial No. 705,898. Term of patent 14 years.

To all whom it may concern:

Be it known that I, HENRY MANN, a citizen of the United States, residing at Milwaukee, in the county of Milwaukee and State of Wisconsin, have invented and produced a new and original Design for Hoops for Barrels and Analogous Articles; and I do hereby declare the following to be a full, clear, and exact description of the same, reference being had to the accompanying drawings, forming a part thereof.

In the said drawings, Figure 1 is a plan view, and Fig. 2 a partly-sectional side elevation, of a barrel-hoop embodying my new design.

My design relates to the new and original shape or configuration of the article.

The leading or essential feature consists in the unitary design for a hoop for barrels or analogous articles made the subject of illustration, comprising a continuous annulus of a nearly-triangular form in cross-section, the inner surface of the annulus being of the greatest transverse length, as shown from a 25 to b, and inclined outwardly from top to bot-

tom, as best shown in section in Fig. 2, while the upper outer surface forms the shortest line of the triangle between the points a and c, and the lower outer surface between the points d and b forms a line of intermediate 30 length, the outer surface of the annulus between the points c and d being rounded, so that the said annulus in cross-section does not follow the exact line of an obtuse-angled triangle, though it approximates that form. 35 The top line a of the annulus forms a continuous annular sharp inner edge, everywhere equidistant from the sharp lower edge b.

Having thus described my invention, what I claim as new, and desire to secure by Letters 40 Patent, is—

The design for a hoop for barrels and analogous articles, substantially as herein shown and described.

In testimony whereof I affix my signature 45 in presence of two witnesses.

HENRY MANN.
